UNITED STATES PATENT OFFICE.

WESLEY E. KEESEE, OF LOS ANGELES, CALIFORNIA.

DESIGN FOR A LUBRICANT-DISPENSING APPARATUS.

Application filed October 22, 1921. Serial No. 509,743. Term of patent 7 years.

To all whom it may concern:

Be it known that I, WESLEY E. KEESEE, a citizen of the United States, residing at Los Angeles, in the county of Los Angeles and State of California, have invented a new, original, and ornamental Design for a Lubricant-Dispensing Apparatus, of which the following is a specification, reference being had to the accompanying drawing, forming a part thereof.

The figure is a side elevation of a lubricant dispensing apparatus, showing my new design.

I claim:

The ornamental design for a lubricant dispensing apparatus, as shown.

WESLEY E. KEESEE.
